(57) **CLAIM**

We claim the ornamental design for a combination flashlight and stun gun, as shown and described.

DESCRIPTION

FIG. 1 is a perspective view of a combination flashlight and stun gun, showing our new design;

FIG. 2 is a top plan view of FIG. 1;

FIG. 3 is a left-side elevational view of FIG. 1, the right-side elevational view being a mirror image thereof; and,

FIG. 4 is a front elevational view of FIG. 1, the rear elevational view being a mirror image thereof.

The broken lines in the figures depict portions of the combination flashlight and stun gun that form no part of the claimed design.
